(57) **CLAIM**

The ornamental design for a vehicle wheel lug-nut having a splined key and frontal indicia, as shown and described.

DESCRIPTION

FIG. 1 is a perspective view of a vehicle wheel lug-nut having a splined key and frontal indicia showing my new design;

FIG. 2 is a right side elevational view thereof; the left side being a mirror image;

FIG. 3 is a top plan view thereof; the bottom being a mirror image;

FIG. 4 is a front elevational view showing the location of a frontal indicia;

FIG. 5 is a rear side elevational view thereof.
The word logo is shown in broken lines in FIGS. 1 and 4 to indicate that a specific Logo pertaining to a specific manufacturer or distributor will be included in the final vehicle wheel lug-nut.
